(57) **CLAIM**

The ornamental design for a slit lamp, as shown and described.

DESCRIPTION

FIG. 1 is a side perspective view of a slit lamp, according to our new design;

FIG. 2 is a back perspective view of the slit lamp according to FIG. 1;

FIG. 3 is an opposing side perspective view of the slit lamp according to FIG. 1;

FIG. 4 is a front perspective view of the slit lamp according to FIG. 1;

FIG. 5 is a perspective view of the slit lamp according to FIG. 1;

FIG. 6 is a perspective view of the slit lamp according to FIG. 1 with parts of the slit lamp in a different orientation; FIG. 7 is a back perspective view of the slit lamp according to FIG. 1 with parts of the SLIT LAMP in a different orientation;

FIG. 8 is a further perspective view of the slit lamp according to FIG. 1;

FIG. 9 is a further perspective view of the slit lamp according to FIG. 1 with parts of the SLIT LAMP in a different orientation;

FIG. 10 is a further side perspective view of the slit lamp according to FIG. 1 with parts of the slit lamp in a different orientation;

FIG. 11 is another front perspective view of the slit lamp shown in FIG. 1;

FIG. 12 is a front perspective view of the slit lamp according to FIG. 11;

FIG. 13 is a further perspective view of the slit lamp according to FIG. 11;

FIG. 14 is a further perspective view of the slit lamp according to FIG. 11;

FIG. 15 is an enlarged portion of the slit lamp shown in FIG. 1;

FIG. 16 is an enlarged portion of the slit lamp shown in FIG. 1;

(Continued)

FIG. 17 is an enlarged portion of the slit lamp shown in FIG. 1;
FIG. 18 is an enlarged portion of the slit lamp shown in FIG. 1; and,
FIG. 19 is an enlarged portion of the slit lamp shown in FIG. 1.
